ATTORNEY.

UNITED STATES PATENT OFFICE.

CHARLES S. MANGENE, OF BOSTON, MASSACHUSETTS.

DESIGN FOR A TILE OR PAVING BLOCK.

46,286.

Specification for Design.

Patented Aug. 18, 1914.

Application filed February 18, 1914. Serial No. 819,584. Term of patent 7 years.

To all whom it may concern:

Be it known that I, CHARLES S. MANGENE, a citizen of the United States, residing at Boston, county of Suffolk, Commonwealth of Massachusetts, have invented a new, original, and ornamental Design for Tile or Paving Blocks, of which the following is a specification, reference being had to the accompanying drawing, forming a part thereof.

Figure 1 is a plan view of the tile or paving block showing my design, and Fig. 2 is a section on the line 2—2 of Fig. 1.

The tile or paving block may be of any suitable material. Extending about its pe-

riphery is a series of intersecting grooves *a* which define an ornamental border. The depth of the grooves *a* is immaterial. The space within the border thus defined is filled with a field of conventional relief such as an inclosed series of depressions *c*. The depth of the depressions is immaterial.

I claim:

The ornamental design for a tile or paving block as shown and described.

CHARLES S. MANGENE.

Witnesses:

VICTORIA LONDEN,
AGNES V. O'CONNELL.
